BEDDING

Leah A. Kay, Amarillo, Tex.

Application November 5, 1947, Serial No. 784,187

17 Claims. (Cl. 5—354)

1

This invention relates to new and useful improvements in bedding, and more particularly to covers such as sheets, and protective articles adapted to be secured on the mattress of a bed.

One object of the invention is to provide an improved bed covering having means thereon for the attachment of other articles of bedding such as a cover sheet, a top sheet, protective and absorbent pads, and the like.

An important object of the invention is to provide a tubular envelope-like sheet which is constructed and arranged to slip onto a mattress and fit tightly thereon to provide smooth, unwrinkled surfaces exposed to the user of the bed. said tubular sheet covering both the upper and lower surfaces as well as the sides of the mattress, whereby the mattress and sheet are reversible so that both surfaces may be used before changing or laundering the sheet.

Another object of the invention is to provide a tubular envelope-like sheet of the character described having means thereon providing for the attachment of a cover sheet or top sheet to said tubular sheet, whereby the top or cover sheet is held in place against displacement by a user, such as an infant or invalid.

A further object of the invention is to provide a tubular envelope-like sheet of the character described having thereon means providing for the attachment of protective articles, such as absorbent and protective pads, protective sheets, and the like.

A further object of the invention is to provide, as an article of bedding, an imperforate water-impermeous protective sheet which is tubular in form and adapted to be slipped onto a mattress to protect the mattress against moisture, said tubular sheet protecting both the upper and lower surfaces of the mattress, as well as the sides, whereby the mattress may be reversed without removing and reattaching the protective sheet.

Still another object of the invention is to provide a tubular envelope-like sheet, of the character described, having detachably secured to one end thereof a top or cover sheet, whereby the top or cover sheet is secured against displacement and cannot be pulled loose by the user of the bed, the means for detachably connecting the tubular sheet and the cover sheet being concealed beneath the mattress and covered against contact or exposure to the user of the bed.

A particular object of the invention is to provide, in combination with a tubular envelope sheet of the character described, detachable protective articles, such as absorbent pads, muslin

2

protective sheets, head pads, and other accessories, which may be varied in size and shape; the protective articles being detachably and reversibly secured in position on the tubular sheet, whereby said protective articles may be reversed in position when the mattress and tubular sheet are turned to permit use of both surfaces thereof.

Still another object of the invention is to provide attachable and detachable protective articles, such as absorbent and protective pads, which are constructed and arranged to be releasably secured to a tubular envelope-like sheet of the character described, for protecting the sheet and mattress against soiling, moisture and the like, and wherein the protective articles include removable absorbent means and imperforate water-impermeous protective means, each separately removable from the tubular sheet.

A still further object of the invention is to provide, in combination, a tubular envelope-like sheet adapted to be slipped on a mattress to cover the same so as to be reversible, whereby both surfaces of the sheet may be used before the sheet is required to be laundered, and protective articles detachably secured to said tubular sheet, and wherein the means for detachably securing the protective articles to the sheet permits positioning of the protective articles at various desired locations with respect to the sheet.

Another object of the invention is to provide bedding of the character described which is simple to use, and which may be readily laundered and sterilized.

A further object of the invention is to provide bedding of the character described which is economical to manufacture and which provides for a saving of material in said manufacture.

Additional objects and advantages of the invention will readily be apparent from the reading of the following description of a device constructed in accordance with the invention, and reference to the accompanying drawings thereof, wherein:

Figure 1 is an isometric view of a tubular envelope-like sheet, constructed in accordance with the invention, and showing the same applied to a mattress.

Figure 2 is a longitudinal vertical sectional view through the device of Figure 1.

Figure 3 is a fragmentary isometric view of the open end of the tubular sheet.

Figure 4 is an isometric view of a sheet constructed in accordance with the invention, and showing protective articles detachably secured in position thereon.

Figure 5 is an enlarged fragmentary sectional view of one end of one of the protective articles of Figure 4.

Figure 6 is an enlarged fragmentary sectional view of the article of Figure 5, taken transversely of the article of Figure 5, and showing the open end, and closure therefor, of the protective article.

Figure 7 is an enlarged fragmentary sectional view of the edge portion of the other protective article of Figure 4, and

Figure 8 is an enlarged fragmentary view, in elevation, illustrating a modified form of the clip used for attaching the protective articles to the tubular sheet.

In the drawings, the numeral 10 designates generally an elongate tubular envelope-like sheet which is formed of an upper substantially rectangular panel of sheet material 11 and a lower panel 12, identical in configuration and size, sewn together at their sides along a seam 13 and at one end along a seam 14, and having an open end 15. The material at the open end of the sheet is folded back upon itself and stitched together separately on each sheet panel to form a hem 16, strengthening the material at such open end of the sheet. The elongate tubular sheet 10 is adapted to slide onto and fit closely about a mattress M, as clearly shown in Figures 1 and 2, to provide smooth unwrinkled surfaces exposed to the user of the bed and covering both the upper and lower supporting surfaces of the mattress, as well as all the sides.

When the sheet is slipped over the mattress in the manner just described, the length of the sheet is such that the open end thereof may be folded downwardly and backwardly under the end of the mattress, as shown in Figures 1 and 2. While any suitable fastening means may be used, it is preferable that elongate tie tapes 17 be sewn or otherwise securely affixed to the marginal edges of the open end 15 of the sheet, and that similar tie tapes 18 be securely sewn or otherwise affixed to the sheet at the seam joining the marginal edges of the sheet panels and located at a point spaced from the open end of the sheet, as best shown in Figure 1, whereby the tapes 17 and 18 on each side may be tied together to securely maintain the open end of the sheet in the folded position under the mattress, completely enclosing the same and holding the sheet taut and preventing longitudinal displacement of the sheet on the mattress.

Manifestly, the end portion of the tubular sheet, which extends beyond the end of the mattress, may be folded in either direction, whereby either the upper sheet panel section 11 or the lower sheet panel section 12 may be exposed for use. Thus, when the sheet has been used in the position illustrated in Figure 1 until it is desired to present a clean fresh sheet surface to the user, it is only necessary to reverse the mattress, turning the upper sheet section 11 downwardly and exposing the lower sheet section 12, and to release the tie tapes 17 and 18 and fold the extended open end portion of the edge sheet about the end of the mattress and back along and below the upper sheet section 11, whereupon the tie tapes 17 and 18 may be retied and the sheet and mattress are again ready for use with the sheet section 12 uppermost and exposed.

It will be seen, therefore, that the tubular envelope-like sheet 10 is tightly fitted onto the mattress and held in position thereon to present smooth top and edge surfaces to contact by the

user, and that the means for securing the sheet in place on the mattress is not exposed to the user. It will further be seen that a substantial saving of material is effected, since each sheet panel section is considerably smaller in length and width than a standard sheet, which standard sheet would necessarily extend downwardly the full height of the side of the mattress and have a sufficient marginal edge portion on each side to tuck under the mattress, and would also have to be of sufficient length to tuck in at the head end of the mattress as well as at the foot end. Furthermore, since each tubular envelope-like sheet may be used on both sides by reversing the mattress and the sheet, as has already been explained, the wear life of the sheet is increased and the laundering necessary is decreased. It has been calculated that it is possible to make two of the tubular envelope-like sheets each having two usable surfaces from approximately the same amount of material that would be required to make three standard single sheets for the same size mattress. Thus, a substantial saving in material is effected.

Fastening means, such as spaced snap type female fastener halves 20 are secured to the hem sections 16 of the open end of the tubular sheet, as clearly shown in Figure 3, such fasteners being affixed on a reinforcing tape 21 which is sewn or otherwise affixed to the hem portion of each sheet section, with the fasteners exposed on the outer surface of such hem sections.

An elongate cover or top sheet 22 hemmed at each end, and of substantially the same length as the tubular sheet 10, has similarly affixed male snap fastener halves 23 secured to the hem portion at one end, whereby said male fastener halves may be snapped into the female fastener halves 20 on the tubular sheet, as clearly shown in Figure 2, to detachably connect the cover or top sheet 22 with the tubular sheet. The cover or top sheet 22 is then folded around the foot end of the mattress and back along the upper surface thereof, overlying the upper sheet section 11, to provide a cover for the user of the mattress and bedding. The fasteners 20 and 23 positively secure the foot end of the cover sheet 22 in place beneath the mattress, and prevent the cover sheet from being pulled loose or displaced by the user of the bedding. Manifestly, the top or cover sheet may be made of blanket material, if desired.

When it is desired that the tubular sheet and the mattress M be reversed, so that the lower sheet section 12 is exposed, the cover or top sheet 22 is unsnapped from the fasteners on the exposed side of the tubular sheet hem 16 and re-fastened to the snap fastener halves 23 on the opposite hem, and the open end of the tubular sheet is untied and folded downwardly and back along the upper sheet section 11 and retied, whereby the cover or top sheet is again secured to the tubular sheet beneath the mattress and the sheets are again ready for use.

In order to protect the mattress against staining or dampening, when the same is used, as by patients in a hospital or for infants, an elongate tubular imperforate water-impervious sheet 25, of rubber or similar material, is slid onto the mattress beneath the tubular sheet 10, the diameter of the rubber tube 25 being such that it closely fits and is held in place on the mattress. Since the tubular rubber sheet 25 extends completely around the mattress, it is obvious that both sides of the mattress are protected when the mattress and the tubular envelope-like sheet

10 are reversed in the manner already described. Furthermore, the tight engagement of the tubular rubber sheet 25 with the mattress prevents wrinkling and displacement of the rubber sheet, and no other means need be provided for holding the tubular rubber sheet in place on the mattress.

15 In using the tubular envelope-like sheet 10, in the care of infants or invalids, it is frequently desirable and necessary that some protective and absorbent article be positioned on the sheet to cover and protect the same against stains, moisture and the like. An embodiment of the tubular sheet of the invention having protective articles detachably secured in position on said sheet to cover and protect the same against stain and moisture is illustrated in Figures 4 through 8 inclusive.

20 The tubular sheet 30 includes an upper sheet panel section 31 and a lower sheet panel section 32, secured together along their longitudinal edges as indicated at 33 and along one end as indicated at 34, to provide the elongate tubular envelope-like sheet 30 open at one end and adapted to be slipped onto and fit snugly about the mattress, in the manner already described. The open end of the tubular sheet is provided with tie tapes 35 at each marginal corner of the open end, and these tie tapes are adapted to be tied to similar tie tapes 36 securely affixed to the sheet at the marginal edge seams 33 on each side of the sheet, whereby the loose open end of the tubular sheet may be folded downwardly and back along and under the lower sheet panel 32 and tied in such position in the manner already described.

25 A plurality of equally spaced washable cloth tape loops 40 are secured between the edges of the upper and lower sheet panel sections 31 and 32 in the longitudinal marginal seams 33, and are diametrically opposed to the loops on the opposite side of the tubular sheet. Each loop projects slightly beyond the marginal seam 33 and is adapted to have the catch arm 42 of a catch member 43 inserted into the loop for connecting a protective article P securely in place on the tubular sheet.

30 Each catch 43 has an eye 44 through which a strap of tape material 45 extends and is sewn as indicated at 46. An oppositely facing catch 47 is securely sewn or otherwise secured to the opposite end of the tape strap 45, as best shown in Figure 4, and the catch arm 48 of said opposite catch is engaged in a cloth tape loop 50, similar to the loop 40, which is securely fixed to the marginal edge of the protective article P.

35 A plurality of equally spaced loops 50 are provided on the protective articles, and these loops are positioned so as to be in alignment with and readily connectable to the loops 40 on the tubular sheet 30. A connecting strap 45 having the catches 43 and 47 at each end is used for connecting each of the loops 50 on the protective article with the corresponding loops 40 on the tubular sheet, whereby the protective article is held tautly in position on the upper surface of the tubular sheet and mattress, and cannot readily be displaced by the occupant of the bed. The straps 45 may be made adjustable in length to accommodate mattresses of different thicknesses, if desired.

40 The protective article P may take many varied forms and shapes, and may constitute any desired combination of protective articles. However, the protective article P illustrated in the

45 drawings includes a substantially rectangular sheet of imperforate water-impervious material 51, preferably of rubber, plastic, or the like, and having the loops 50 secured at spaced points along its longitudinal edges in the manner best illustrated in Figure 5. The loops are sewn or otherwise suitably secured to the underside of the rubber sheet 51, being disposed between said sheet and a strengthening tape 52, while a similar strengthening tape 53 having male snap fastener halves 54 secured at spaced points therealong is similarly sewn or otherwise secured to the upper marginal edge of the rubber sheet. Thus, the rubber sheet may be securely and tautly affixed on the upper surface of the tubular cover sheet 30 to protect the sheet against stains, dampening, and the like.

50 If it is desired that an absorbent pad be included in the protective article P, it is preferable that the pad be formed of a rectangular envelope 55, made of toweling, mesh material, or the like, having an inner sheet 56 and an outer sheet 57 sewn together along three marginal edges as indicated in Figure 5, whereby an envelope-like receptacle having an open end is provided for receiving and enclosing a mass of absorbent material 58. Thus, the envelope and absorbent material forms a pad for absorbing moisture, stains, and the like. A reinforcing tape 59, having female snap fastener halves 60 secured thereon, is sewn to the marginal edges of the envelope, whereby the male fastener halves 54 on the marginal edges of the rubber sheet 51 may be engaged in the female snap fastener 55, to securely detachably affix the absorbent pad envelope to the rubber sheet. Therefore, the absorbent pad envelope having the absorbent material confined therein is positively detachably held in place above the rubber sheet 51, whereby the absorbent material in the envelope will absorb moisture and the like, and the rubber sheet will prevent the moisture from traveling from the absorbent material to the sheet 30 and mattress therebelow.

55 Manifestly, if desired, the upper sheet panel 57 of the absorbent pad envelope 55 may be provided with a projecting flap 61 along the open end of the envelope, and this flap 61 may be turned downwardly and inwardly along and below the lower sheet panel 56 to close the open end of the envelope and prevent the absorbent material 58 from being displaced from within the envelope. Or, flaps may be provided on both the upper and lower sheet panels, if desired.

60 The protective pad may take various shapes and forms, as has already been explained, and a small head pad adapted to be secured at the head end of the bed for protecting the bed against stains and moisture is shown in Figure 4. The pad construction is the same as that of the protective article P, which has already been described, the difference being that the head pad H is smaller and may form a separate protective article from a body pad or other article secured at other positions on the tubular sheet 30 and mattress.

65 Manifestly, the imperforate water-impervious sheet 51 may be reversed in position when the mattress is turned to expose the lower sheet section 32 for use by the patient or infant. This reversal of the rubber sheet may be effected by loosening the catches 43 from the loops 40 along one side of the tubular sheet and swinging the sheet about the loops on the other side of the

sheet until the rubber sheet is positioned above the lower sheet panel 32, whereupon the catches 43 may be reengaged with the loops 40 to securely affix the rubber sheet in place for protecting said sheet panel. Also, male snap fastener halves 54' may be secured on the reinforcing tape 52 opposite the fastener halves 54, whereby the protective pad envelope may be detachably connected to the opposite side of the rubber sheet in the manner already described, by snapping the male fastener halves 54' into the female fastener halves 60 of the protective article.

If desired, the protective article may be modified in the manner illustrated in Figure 7, wherein the protective article P' includes an absorbent material containing envelope 65 formed with an inner sheet 66 and an outer sheet 67 of suitable material, such as toweling or mesh material, for enclosing and holding a mass of absorbent material 68 therein. The marginal edges of the sheets of the envelope are sewn or otherwise secured together with the inner ends of the loops 69 secured therebetween. Reinforcing tape strips 70, having female snap fastener halves 71 secured thereto at spaced points, are sewn or otherwise secured to each outer side of the marginal edge of the envelope. One marginal edge of the envelope 65 is left unsewn, whereby the absorbent material 68 may be readily inserted within said envelope.

A sheet of imperforate water-impervious material 72, such as rubber, plastic or the like, has a reinforcing tape 73 secured along its marginal edges, and this tape carries spaced male fastener halves 74 adapted to be snapped into the female snap fastener halves 71, whereby the rubber sheet may be securely detachably affixed or connected to one side of the absorbent pad envelope 65.

The envelope 65 is fully reversible, when the mattress and tubular sheet 30 are turned to present the lower sheet panel section 32 for use by the occupant of the bed, by loosening the catches 43 from the loops 69 and turning the envelope to position it above the sheet section 32. The catches are then reengaged with the loops to again secure the envelope in place.

The absorbent material 68 in the protective article P' may be a mass of toweling, quilted absorbent cotton, or similar washable and reusable absorbent material. Or, such absorbent material may be formed of disposable absorbent material, such as paper toweling, paper diaper material, or the like.

The catch member for connecting the loops 40 of the tubular sheet and the loops 50 of the protective article may take the shape illustrated in Figure 8, wherein the catch 43a is substantially S-shaped and has a catch arm 42a at its lower end and a similar oppositely directed catch arm 44a at its upper end. The catch arms are adapted to be inserted into the loops 40 and 50 to detachably connect the loops and thus detachably secure the protective article in place on the tubular sheet. Manifestly, other forms of catches may be employed instead of the catches illustrated, as for example snap fasteners.

From the foregoing, it will be seen that an improved bed covering has been provided having means thereon for the attachment of other articles of bedding, such as a cover sheet, a top sheet, protective and absorbent pads, and the like. It will also be seen that the bed covering constitutes a tubular envelope-like sheet which is constructed and arranged to slip onto a mattress and fit tightly thereon to present smooth un-

wrinkled surfaces exposed to the user of the bed, said tubular sheet covering both the upper and lower supporting surfaces of the mattress, as well as its sides, whereby the mattress and sheet are reversible so that both surfaces may be used without changing or laundering the sheet. Furthermore, the accessories, such as the cover sheet or top sheet, protective and absorbent pad, and the like, which are detachably secured to the tubular sheet, may be reversed when the tubular sheet and mattress are reversed. It will also be seen that the tubular envelope-like sheet has means provided thereon for the releasable attachment of a cover sheet or top sheet to the foot of the tubular sheet, whereby the cover or top sheet is held in place against displacement by the user, such as an infant or invalid; and, that the attaching means permits the top or cover sheet to be secured to either sheet panel section of the tubular sheet, whereby the cover sheet may be secured to said tubular sheet to cover the exposed sheet panel section, regardless of which is uppermost and exposed for use. Also, the cover sheet may be made of blanket material, if desired.

Furthermore, the top or cover sheet which is detachably connected to the tubular envelope-like sheet is secured against displacement by the user and the snap fasteners are covered against contact or exposure to the user of the bed and are concealed beneath the mattress.

It is also manifest that an imperforate water-impervious protective sheet has been provided which is tubular in form and which is adapted to be slipped on to the mattress to protect the same against moisture, staining and the like; said sheet being so constructed and arranged as to protect both the upper and lower supporting surfaces of mattress, as well as the sides thereof, whereby the mattress is completely protected and may be reversed without removing and reattaching the tubular protective sheet.

It is believed to be clearly apparent that various types of protective articles, such as absorbent pads, muslin protective sheets, head pads, and other accessories of various sizes and shapes, may be detachably and reversibly secured in position on the tubular sheet, whereby the protective articles may be reversed in position when the mattress and tubular sheet are turned to permit use of both surfaces thereof, and whereby a plurality of various accessories may be simultaneously independently secured to the tubular sheet as desired.

It will further be seen that the tubular envelope-like sheet is simple to use and may be readily laundered and sterilized, there being no metallic fastening means which would stain or tear the tubular sheet. Furthermore, the tubular sheet is economical to manufacture, and provides for a substantial saving of material in manufacture, since two of the tubular sheets, each having two usable surfaces, may be made from substantially the same amount of material required to make three single sheets for the same size mattress.

The tubular sheet is particularly adapted for use on the beds of infants, but may as readily be used on invalid beds and the like, if desired. The accessories are also particularly adapted for use in the care of infants; but, as has been explained, may as readily be used in the care of invalids and adults. Obviously, accessories other than those shown and described may be detachably secured in position on the envelope-like tu-

ular sheet and may be reversed in position thereon when the sheet is reversed, as has already been explained.

The foregoing description of the invention is explanatory only, and changes in the details of the constructions illustrated may be made by those skilled in the art, within the scope of the appended claims, without departing from the spirit of the invention.

What I claim and desire to secure by Letters Patent is:

1. An article of bedding including, an envelope formed of a pair of substantially rectangular sheet panels joined together along their longitudinal marginal edges and at one end margin and having their other end unjoined to provide an opening whereby the envelope may be slipped onto a mattress or the like, the size of the envelope being such that it fits snugly on said mattress with the open end of the envelope projecting beyond the end of the mattress whereby said open end portion of the envelope may be folded back along one sheet panel, and releasable means for securing said open end portion of the envelope in such folded position.

2. An article of bedding of the character set forth in claim 1 wherein, the open end portion may be folded back along either sheet panel as desired, and the releasable securing means is constructed and arranged to secure said open end portion in such folded position with respect to either sheet panel.

3. An article of bedding of the character set forth in claim 1 wherein, the releasable securing means includes releasable fastening means at each corner of the open end of the envelope, and coacting releasable fastening means on each longitudinal marginal edge of the envelope spaced from the open end thereof and arranged to be detachably engaged with the fastening means at each corner of the open end of the envelope to adjustably secure the open end of the envelope in folded enclosing position, said securing means being positioned so as to be spaced from the supporting surfaces of the mattress enclosed by the envelope.

4. An article of bedding of the character set forth in claim 1 wherein, either of the two sheet panels may be exposed for use, whereby the envelope provides a reversible bottom sheet for the mattress.

5. An article of bedding including, an envelope of sheet material having an open end and adapted to be slipped onto and to fit snugly on a mattress to cover the supporting surfaces of said mattress, and a plurality of spaced fastening loops carried by the envelope at its marginal edges disposed to be positioned between the upper and lower supporting surfaces of the mattress when the envelope is in place on said mattress.

6. An article of bedding including, an envelope of sheet material having an open end and adapted to be slipped onto and fit snugly on a mattress to cover the supporting surfaces of the mattress, releasable means for securing the open end of the envelope in a position completely enclosing the mattress, and a plurality of fastening means carried by the envelope and disposed at the side of the mattress and between the upper and lower supporting surfaces thereof when the envelope is in place on the mattress.

7. An article of bedding including, an envelope formed of a pair of substantially rectangular sheet panels joined together along their longitudinal edges and at one end margin and having

their other end unjoined to provide an opening whereby the envelope may be slipped onto a mattress, the size of the envelope being such that it fits snugly on said mattress with the open end of the envelope projecting beyond the end of the mattress whereby said open end portion of the envelope may be folded back along one sheet panel to completely enclose the mattress, releasable means for securing said open end portion of the envelope in such folded position, and a plurality of spaced fastening means carried by the envelope along the seams at the marginal edges of the envelope.

8. An article of bedding of the character set forth in claim 7 wherein, the spaced fastening means carried by the envelope includes loops of cloth tape material secured between the sheet panels and projecting beyond the marginal edge thereof, whereby fasteners may be inserted in said loops to attach accessories to the envelope.

9. An article of bedding including, an envelope formed of a pair of substantially rectangular sheet panels joined together along their longitudinal edges and at one end margin and having their other end unjoined to provide an opening whereby the envelope may be slipped onto a mattress, the size of the envelope being such that it fits snugly on said mattress with the open end of the envelope projecting beyond the end of the mattress whereby said open end portion of the envelope may be folded back along one sheet panel to completely enclose the mattress, releasable means for securing said open end portion of the envelope in such folded position, a plurality of spaced fastening means carried by the envelope along the seams at the marginal edges of the envelope, and a plurality of spaced fastener means on the outer surface of the marginal edge of the open end of each sheet panel of the envelope.

10. An article of bedding including, an envelope formed of a pair of substantially rectangular sheet panels joined together along their marginal longitudinal edges and at one end margin and having their other end unjoined to provide an opening whereby the envelope may be slipped onto a mattress, the size of the envelope being such that it fits snugly on said mattress with the open end of the envelope projecting beyond the end of the mattress whereby said open end portion of the envelope may be folded back along one sheet panel to completely enclose the mattress, releasable means for securing said open end portion of the envelope in such folded position, a plurality of spaced fastening means carried by the envelope along the seams at the marginal edges of the envelope, and a protective article on the exposed surface of the covered mattress and detachably secured to said spaced fastening means carried by the envelope.

11. An article of bedding of the character set forth in claim 10 wherein, the spaced fastening means carried by the envelope includes loops of cloth tape material secured between the sheet panels at the marginal seam and projecting beyond the marginal edge thereof, and detachable fastener means constructed and arranged to be inserted in said loops to releasably attach the protective article to the envelope.

12. An article of bedding of the character set forth in claim 10 wherein, the means for releasably securing the open end portion of the envelope in folded position is constructed and arranged to permit the open end portion to be

folded along either sheet panel, whereby the other sheet panel may be exposed for use and the envelope provides a reversible bottom sheet for the mattress, and wherein the protective article secured to the envelope is also reversible to protect either sheet panel of the envelope.

13. An article of bedding including, an envelope of sheet material having an open end and adapted to be slipped onto and fit snugly on a mattress to cover the supporting surfaces of said mattress, releasable means for securing the open end of the envelope in a position completely enclosing the mattress, a plurality of spaced fastener means on the outer surface of the marginal edge of the open end of the envelope, and a cover sheet having a plurality of spaced fastener means at one end constructed and arranged to be engaged with the fastener means on the envelope to secure the end of the cover sheet to the open end of the envelope, whereby the cover sheet may be folded back along the uppermost surface of the envelope. 20

14. An article of bedding of the character set forth in claim 13 wherein, a plurality of spaced fastener means is provided on the outer surface of the marginal edge of each panel of the envelope at the open end of said envelope. 25

15. An article of bedding including, an envelope of sheet material having an open end and adapted to be slipped onto and fit snugly on a mattress to cover the supporting surfaces of said mattress, releasable means for securing the open end of the envelope in a position completely enclosing the mattress, a plurality of fastening means carried by the envelope and disposed at the sides of the mattress and spaced from the upper and lower supporting surfaces thereof when the envelope is placed on the mattress, a protective sheet of imperforate water-impervious material, and fastening means carried by said sheet of water-impervious material at its marginal edges and arranged to engage with the fastening means carried by the envelope for positively detachably securing said protective sheet on the exposed surface of the envelope for 40

protecting the same against moisture and the like.

5 16. An article of bedding of the character set forth in claim 15 wherein, the protective sheet of imperforate moisture-impervious material is provided with fasteners at its marginal edges, whereby an absorbent article may be detachably secured to said protective sheet.

10 17. An article of bedding including, an envelope of sheet material having an open end and adapted to be slipped onto and to fit snugly on a mattress to cover the supporting surfaces of the mattress, releasable means for securing the open end portion of the envelope in a position 15 completely enclosing the mattress, an accessory adapted to be secured in position on the exposed surface of the envelope, and means for detachably securing the accessory in position on such exposed surface of the envelope.
